UNITED STATES PATENT OFFICE.

JOSEPH E. NORMAND, OF WATERTOWN, NEW YORK.

EQUALIZING-LEVER.

SPECIFICATION forming part of Letters Patent No. 660,649, dated October 30, 1900.

Application filed July 29, 1899. Serial No. 726,456. (No model.)

To all whom it may concern:

Be it known that I, JOSEPH E. NORMAND, a citizen of the United States of America, and a resident of Watertown, Jefferson county, 5 New York, have invented certain new and useful Improvements in Equalizing-Levers, of which the following is a specification.

This invention relates to a system of equalizing-levers for a combined power and hand 10 brake mechanism of a railroad-car brake. The system is especially adapted for use in connection with a double-truck street-railroad car, but of course is not limited to such use.

My invention consists in a system of equalizing-levers adapted for use with a power-brake which may be readily added to the foundation-rigging of a hand-brake system, such as is commonly in use on a street-car, and when so attached may be used independently of and without interfering with the hand-lever or connecting-rods, and, further, that the hand-brake system shall still be free to be used in place of the automatic when desired.

25 I will now proceed to describe an equalizing system embodying my invention and will then point out the novel features in a claim.

In the accompanying drawings, Figure 1 illustrates a portion of a car-framing and a 30 system of equalizing-levers embodying my invention, and Fig. 2 is a central longitudinal section through the brake-cylinder.

Similar reference characters designate corresponding parts in both figures.

35 Reference character 1 designates the car-framing, 2 the hand-brake lever, and 3 connecting-rods leading to the hand-brake staffs.

40 4 designates an air-brake cylinder of any desired or well-known form. This cylinder and its appurtenances are shown in detail section in Fig. 2. The pump, governor, and valve system are not shown in detail herein, as not forming part of the invention; but the said cylinder may be provided with the usual 45 operating-valve adapted to admit compressed air thereto from a source of supply and to discharge air therefrom as it is desired to "set" or "release" the brakes. One end of an air-reservoir is shown in the drawings and 50 is designated by the reference character 18.

55 15 designates a piston with which the cylinder is provided, having a hollow piston-rod

16. A spring 14 is arranged within the cylinder for returning the piston to its normal position.

5 5 designates a rod arranged to slide loosely in the hollow piston-rod 16 and to bear at one end against the piston 15 within the cylinder, and at the other end it is secured at 17 to a link 6, in turn secured to an intermediate lever, (designated by the reference character 7.) The lever 7 is fulcrumed at a fixed point 8 upon the frame of the car.

9 and 10 are two levers known as the "cylinder-levers," the one fulcrumed to the end 65 of the cylinder and the other, commonly known as a "floating" lever, from the fact that its fulcrum is not a fixed point, pivoted to the link 6 at 17. 11 is a connecting-link securing the two levers together intermediate of 70 their length. The opposite ends of the cylinder-levers 9 and 10 are pivoted to the connecting-rods 12, leading to the truck-levers in a manner well known.

The lever 7 is connected to the hand-brake 75 lever 2, preferably by a flexible connection 13, such as a chain. This flexible connection will permit the using of the automatic or air brake without interfering with the hand-brake lever 2 or connecting-rods 3, &c. When 80 the automatic brake mechanism is used, slack is formed in the chain connection 13, which is taken up again when the brakes are released and the parts returned to their normal position.

85 When it is desired to use the hand-brakes, one of the connecting-rods 3 is drawn forward by any suitable and well-known hand-operated mechanism—such as the ordinary hand-brake, staff, and chain connection—and the 90 rod 5 is drawn out and the brakes set thereby, precisely as if motive fluid had been introduced into the cylinder 4. It will thus be seen that the hand mechanism and the power mechanism may be used entirely independent 95 of the other. At the same time the same system of levers is used in either case and operated from the same point—that is, at the point 17—when the link 6 and rod 5 are both secured to the lever 10. In the use of the 100 hand brake mechanism, however, an additional lever is thrown in—namely, 7—in order to give greater purchase.

By my arrangement of levers I have shown

an exceedingly simple and effective equalizing system and one which upon being added to a car originally equipped for hand-brake only in no way interferes with the foundation 5 brake-rigging. It simply means the addition of three levers.

What I claim is—

In a brake-operating mechanism, the combination with a cylinder and piston mounted 10 therein, two cylinder-levers, the one pivoted to a fixed point of support and the other constituting a floating lever, a link connecting the two levers together at points intermediate of their ends, and truck-lever connecting-rods 15 pivoted to the ends of said cylinder-levers, of a hand-brake lever centrally pivoted to a fixed point of support, hand-brake connecting-rods connected to opposite ends of same, an inter-

mediate lever pivoted at one end to a fixed point of support, a flexible connection between 20 the opposite end thereof and the hand-brake lever, a connection between the power end of said floating cylinder-lever and the intermediate lever at a point intermediate of its length, and a connection between said piston 25 and the power end of said floating lever, whereby said lever may be operated by the movement of said piston, but is free to be operated by said hand-brake lever independently of said piston..

Signed by me at New York, N. Y., this 26th day of July, 1899.

JOSEPH E. NORMAND.
